UNITED STATES PATENT OFFICE.

HARRISON H. ROUNTREE, OF CHICAGO, ILLINOIS.

DESIGN FOR A SPROCKET-WHEEL AND CHAIN GUARD.

SPECIFICATION forming part of Design No. 27,182, dated June 8, 1897.

Application filed April 28, 1897. Serial No. 634,298. Term of patent 3½ years.

To all whom it may concern:

Be it known that I, HARRISON H. ROUNTREE, a citizen of the United States, and a resident of Chicago, in the county of Cook and State 5 of Illinois, have invented and produced a new and original Design for Sprocket-Wheel and Driving-Chain Guards or Shields for Bicycles, of which the following is a specification.

In the accompanying drawings, Figure 1 is 10 a perspective view of a guard or shield embodying my design. Fig. 2 is a longitudinal sectional view thereof on the line 2 2 of Fig. 1, and Fig. 3 is a transverse sectional view thereof on the line 3 3 of Fig. 1.

15 My present design embraces a marginal frame A, having an unbroken or smooth exterior surface and provided with a flange A', which projects laterally from the outer border of the frame A in a position to cover the 20 front sprocket and driving-chain of a bicycle when the guard is properly secured to the frame thereof.

The essential feature of my present design embodies a light ornamental border B within 25 the marginal frame A and extending parallel with the edges thereof, said border, as shown, comprising a series of small loops b, which are attached to the inner edge of the margin-

nal frame A, said loops b being connected by a series of bars b', which curve inward away 30 from the marginal frame.

At a proper point of the guard the opposite curved bars b' are connected by an open-work web or scroll B', the front edges b² of which, in conjunction with the curved bars b' of the 35 border B at the front end of the guard, define a circular opening or space, the rear edge b³ of said web or scroll B' constituting the forward limit of a large somewhat flaring space, the longitudinal limits of which are defined 40 by the curved bars b', connecting the loops b along the longitudinal parts of the marginal frame A.

I claim—

The design for sprocket-wheel and chain 45 guards, substantially as herein shown and described.

In testimony that I claim the foregoing as my invention I hereunto set my hand, this 21st day of April, 1897, in the presence of two 50 witnesses.

HARRISON H. ROUNTREE.

Witnesses:
